UNITED STATES PATENT OFFICE.

JESSE L. LAMONT, OF GENESEO, ILLINOIS.

SIGNAL.

Application filed February 12, 1927. Serial No. 167,837.

This invention relates to railroad crossing signals.

An object of the invention is the provision of a device for displaying a warning signal at a railroad crossing which is automatically positioned through the operation of a mechanism actuated by the moving train before it reaches the crossing, the signal being moved to an inoperative position by the moving train after the crossing has been passed.

A further object of the invention is the provision of a signal adapted to be automatically displayed as a warning to traffic at a railway crossing and which is moved to an operative position through a mechanism actuated by the wheels of the train before said train reaches the crossing. A similar mechanism, but reversely actuated, being adapted to cause the signal to be moved to an inoperative position after the train has moved beyond the railway crossing.

This invention will be best understood from a consideration of the following detailed description, in view of the accompanying drawing forming a part of the specification; nevertheless, it is to be understood that the invention is not confined to the disclosure, being susceptible of such changes and modifications which shall define no material departure from the salient features of the invention as expressed in the appended claims.

Figure 1 is a plan view showing my signal applied to a railroad at a crossing,

Figure 2 is a longitudinal section taken along the line 2—2 of Figure 1,

Figure 3 is a fragmentary side view showing part of the operating mechanism of the signal,

Figure 4 is a side view showing the signal in an operative position and the connections with the actuating mechanism,

Figure 5 is a transverse vertical section taken along the line 5—5 of Figure 1.

Referring more particularly to the drawings, 10 designates a road bed passing over a railway having rails 11 and cross ties 12.

The signal shown at 13 is slidably mounted in posts 14 and 15 adapted to be normally rocked within a housing 16 carried by the upper ends of the post. The signal is shown in its operative position for warning the public when a train is approaching, the signal being supplied with indicia to that effect. A housing may be placed at the rear

of the signal and provided with lamps so that said signal will be illuminated at night when the same is placed in an operative warning position and contacts may be carried by the moving signal for engaging the contact forming terminals of an electric circuit, whereby the lamps may be automatically lighted when the signal is moved to its operative position. The signal may be transparent through which the light rays are projected or the lamps may be located in a convenient position for illuminating an opaque signal.

The signal is immediately actuated by an arm 17 pivoted at 18 to the top of the signal and also pivoted at 19 on the post 15 and rigid with an arm 20, the arms 17 and 18 forming a bell crank lever. A link 21 is pivotally connected at its ends, respectively, with the arm 20 and a lever 22 rigid with a shaft 23 mounted in bearings 24 on a post or bracket 25. The shaft 23 also is provided with an arm 25^a having the slot 26 into which is inserted a pin 27 connected with the upper free end of an arm 28 rigid with the shaft 29. The shaft is mounted in bearings 30 carried by a second block 31 extending downwardly from the shaft 29 and rigid therewith is an arm 32 provided with a slot 33 receiving a pin 34 carried by a connection 35. The connection 35 secures the links 36 and 37 together. The links 36 and 37 may be formed of one piece and the connection 35 may be a sleeve slipped onto the rod and secured to the same in any approved manner.

The elements designated by the numerals 17 to 37 inclusive form the connecting means between the signal 13 and the mechanism actuated by the train for causing proper positioning of the signal to warn the public.

An actuating mechanism including a tripping means which comprises a pair of bars 38 and 39 pivotally connected together at 40 and have flanges 41 adapted to be engaged by a flange of the wheels of the trains for depressing the inner elevated ends of said bars and these bars at their outer ends are pivoted upon U-shaped brackets 42 secured to beams 43 by means of bolts 44. The beam 43 is attached to the cross ties 12 in any approved manner.

A shaft 45 is mounted for rotation in a bearing 46 from which depends an arm 47 at the outer side of the bearing 46. At the inner side of said bearing is a toe 48 which is

rigidly connected with the shaft 45 and has an inclined portion 49 adapted to be engaged by the underface of a flange 41 of the bar 39 when said bar is depressed. A link 50 connects the lower end of the arm 47 with the outer end of the link 37 as shown at 51.

A mechanism is also employed at the opposite side of the crossing 10 for causing the signal to be moved to an inoperative position after the train has passed. This mechanism is actuated by the moving train after the rear end of the train has passed the crossing. This device is similar to the actuating mechanism of the signal and comprises a pair of bars 52 and 53 pivotally connected at their inner ends as shown at 54. These bars are flanged as shown at 55 and adapted to be engaged by the flanges of the wheels. A toe 56 rigid with a shaft 57 carried in a bearing 58 mounted on the beam 59 is adapted to engage beneath the flange 55 of the bar 52. A lever 60 is rigid with the outer end of the shaft 57 and is connected at its lower end to the link 36 by means of a link 61.

The operation of my device is as follows:

The wheels of the train approaching the crossing 10 will move over the bar 39 forcing said bar downwardly and likewise bar 38. The flange 41 of bar 39 engages the free end 49 of the toe 48, oscillating said toe and rocking the arm or lever 47 in a direction indicated by the arrow in Figure 3. The outer free end of the lever pulls on the links 50 and 37 thereby moving the arm or lever 32 to the position shown in Figures 2 or 4 so that the arm 28 is moved to the left, oscillating the lever 22 in a direction indicated by the arrow in Figure 4. As the outer end of the lever 22 is moved downwardly, the lower end of the arm 20 has been moved upwardly, depressing arm 17 and lowering the signal 13 to view as a warning.

After the train has passed the crossing 10, the wheels will come in contact with the bar 53 and thereby depressing the bar 52 and toe 56. This movement rocks shaft 57, thereby moving lever or arm 60 as indicated by the arrow in Figure 2, causing link 36 to be moved to the left and reversely rocking arms 32 and 28, this causes the upper end of the arm 22 to be moved in the direction which is opposite to the direction indicated by the arrow in Figure 4, whereby the arm 20 is rocked towards the post 14, thereby elevating arm 17 and moving the signal 13 into the housing 16.

It will be noted that there are no springs, cables or pulleys employed in the mechanism actuating the signal and only a right and left end trip are required upon opposite sides of the railroad crossing 10 and connected by links which are of sufficient length to allow the train to pass between the trips so that both trips will not be actuated at the

same time. All of the operating elements are inclosed in a housing, except the tripping device which comprises the pivoted bars 38 and 39 and 52 and 53.

I claim:

1. A signaling device for grade crossings comprising a housing, a signal normally mounted in the housing and means for moving said signal out of said housing, said means including a pair of bars pivotally connected together at their inner ends and having their outer ends pivotally mounted on a fixed support, a toe engaged by one of the bars and adapted to be rocked when the bars are depressed by the wheels of the train, a shaft rigid with the toe, an arm rigid with the shaft, a second rock shaft, an arm depending from said rock shaft and a link connecting the respective arms of the shafts, a bell crank lever, means connecting an arm of the bell crank lever with the second mentioned rock shaft, the other arm of the bell crank lever being connected with the signal when said bars are depressed, the bell crank lever being actuated to move the signal out of the housing.

2. A signaling device for grade crossings comprising a housing, a signal normally mounted in the housing and means for moving said signal out of said housing, said means including a pair of bars pivotally connected together at the inner ends and having their outer ends pivotally mounted on a fixed support, a toe engaged by one of the bars and adapted to be rocked when the bars are depressed by the wheels of the train, a shaft rigid with the toe, an arm rigid with the shaft, a second rock shaft, an arm depending from said rock shaft and a link connecting the respective arms of the shafts, a bell crank lever, means connecting an arm of the bell crank lever with the second mentioned rock shaft, the other arm of the bell crank lever being connected with the signal when said bars are depressed, the bell crank lever being actuated to move the signal out of the housing, and means connected with the first mentioned rock shaft and adapted to be actuated by the moving train for reversely rocking said shaft whereby the signal is returned to the housing.

3. A signaling device for grade crossings comprising a housing, a signal normally mounted in the housing and means for moving said signal out of said housing, said means including a pair of bars pivotally connected together at the inner ends and having their outer ends pivotally mounted on a fixed support, a toe engaged by one of the bars and adapted to be rocked when the bars are depressed by the wheels of the train, a shaft rigid with the toe, an arm rigid with the shaft, a second rock shaft, an arm depending from said rock shaft and a link connecting the respective arms of the shafts,

a bell crank lever, means connecting an arm of the bell crank lever with the second mentioned rock shaft, the other arm of the bell crank lever being connected with the signal when said bars are depressed, the bell crank lever being actuated to move the signal out of the housing, a third rock shaft spaced from the first mentioned rock shaft,

means for causing rocking of the third rock shaft, and means operatively connecting the first and last mentioned rock shaft whereby positive actuation of the last mentioned shaft will cause reverse rotation of the first rock shaft and return of the signal to the housing. 10

JESSE L. LAMONT.
